Dec. 15, 81

To all whom it may concern,

Be it known that I, Charles J. Woolson, of Cleveland, Ohio, have produced a new and original design for Cooking Stoves, and I hereby declare that the following is a full and exact description thereof, reference being had to the accompanying drawing, in which my ornamental design is clearly represented.

The shape and configuration of the plates are designated by the general outline of the drawing.

The ornament upon the doors is seen at A, in figures 1, 2, 3, 4 and 6. The ornament upon the legs at B.

Having thus distinctly represented and described the ornamental work upon my cooking stove.

I claim the same as new and desire to secure by Letters Patent, the configuration and arrangement of said ornamental work as hereinafter designated and represented.

Witnesses,

R. B. Carter.
W. G. Carter.
